UNITED STATES PATENT OFFICE.

JOHN HENRY DAVIS, OF ELIZABEHTOWN, KENTUCKY.

HARROW.

SPECIFICATION forming part of Letters Patent No. 722,287, dated March 10, 1903.

Application filed May 29, 1902. Serial No. 109,530. (No model.)

To all whom it may concern:

Be it known that I, JOHN HENRY DAVIS, a citizen of the United States, residing at Elizabethtown, in the county of Hardin and State 5 of Kentucky, have invented a new and useful Harrow, of which the following is a specification.

My invention is an improved harrow; and it consists in the peculiar construction and 10 combination of devices hereinafter fully set forth and claimed.

In the accompanying drawings, Figure 1 is a side elevation, partly in section, of a harrow constructed in accordance with my invention. Fig. 2 is a top plan view of the same. Fig. 3 is a detail sectional view of one of the harrow-teeth.

In the embodiment of my invention here shown I employ an axle 1, on the ends of 20 which are a pair of traction and supporting wheels 2. A suitable tongue or other draft element 3 is attached to the axle, and a platform 4 is at the rear of the tongue and on the axle. The frame thus constructed is provided 25 with a seat 5 for the driver.

A revoluble harrow-cylinder 6 has its bearings in the rear ends of a pair of supporting bars 7. The front ends of the said supporting-bars are pivotally connected to the axle 30 1, as here shown, or they may be otherwise pivotally supported, and I do not limit myself in this particular. A lever 8, which is mounted on the frame, has an arm 9, which is connected to one of the bars 7 by a link or other suitable connecting element 10, and hence by means of said lever and said bars 7 the revoluble harrow-cylinder may be raised and lowered, as will be understood. A segment 11 is provided and the lever 8 has a 40 locking-dog 12 of the usual construction to engage the segment, and hence the lever may be locked at any adjustment to support the revoluble harrow-cylinder at any desired elevation.

45 Each of the cylinder-supporting bars comprises a pair of sections 7^a 7^b, flexibly connected together, as by a pivotal joint 7^c, and the rear section 7^b has a forwardly-projecting stop-arm 7^d to engage the under side of the 50 section 7^a. Hence the flexibly-jointed supporting-bars may be bent downwardly, but not upwardly. This enables the harrow-cylinder

to be raised by the supporting-bars and also enables the harrow-cylinder when the same is in operation on the ground to rise and pass 55 over an obstruction, such as a stump or stone.

The revoluble harrow-cylinder may be of any suitable construction. As here shown, it comprises a plurality of circular heads 13, disposed at suitable distances apart on an axle- 60 shaft 14, and bars 15, which are secured on the peripheries of the heads, are disposed longitudinally of the cylinder and connect the heads together. The bars carry teeth which project from the outer sides thereof and are 65 disposed radially with respect to the harrow-cylinder. At one end of the harrow-cylinder shaft or axle is a sprocket-wheel 16. A sprocket-wheel 17 of greater diameter rotates with one of the wheels 2, and an endless 70 sprocket-chain 18 connects the said sprocket-wheels. Hence the harrow-cylinder is revolved by the power of one of the traction-wheels 2 and at a higher rate of speed than would be the case if the harrow-cylinder 75 were rotated by frictional contact with the ground.

In operation the harrow-cylinder is lowered to cause its teeth to enter the soil to any desired extent, and the lever 8 is then locked, so 80 that the weight of the revoluble harrow-cylinder is carried by the supporting-bars 7. As the machine advances the teeth carried by the revolving harrow-cylinder cut through and break up the clods, thereby placing the 85 ground, which has been previously plowed, in excellent condition for planting. The harrow-teeth are preferably of the form shown in Figs. 1 and 3, being sharpened at one edge, as at 19, beveled on one side, as at 20, and 90 beveled only for a portion of a distance on the opposite side. The harrow-teeth are designated by the numeral 22. In practice I prefer to construct the harrow-teeth with shanks 23 at their inner ends, which are angular in 95 cross-section, to fit in corresponding openings in the bars 15 and provide them with threaded sections or shanks 24, on which are screwed nuts 25, that clamp the teeth to the bars. Hence the harrow-teeth may be readily removed and renewed or sharpened when they 100 become broken or dulled.

My improved harrow is provided with a roller 26, which operates in advance of the

revoluble harrow-cylinder, and is here shown as being journaled in the lower ends of a pair of arms 27, which have their upper ends pivotally connected to the axle-shaft 1, as at 28.

5 This roller may be of any suitable construction and may be connected to the harrow by any suitable means. I do not limit myself to the use of the roller in connection with my improved harrow, as the same may be dispensed with, if preferred. When used, the roller breaks the clods in advance of the revoluble harrow - cylinder and facilitates the action of the latter in preparing the ground for planting.

15 It is obvious that the arms 27 may be of such length as to cause the roller 26 to operate in rear of the revoluble harrow, as indicated by dotted lines in Fig. 1 of the drawings. When the roller is thus used, it leaves 20 the ground smooth after the harrow, ready for the planter. Hence my improved harrow may be used effectively on land in any condition, whether hard and full of clods or soft and friable.

25 Having thus described my invention, I claim—

1. In an implement of the class described, the combination of a wheel-supported main frame, a harrow-supporting frame having

jointed side pieces, the front members of 30 which have pivotal connection with the axle of the main frame, a shaft connecting the rear members of said frame, a rotary harrow element supported upon said shaft, projections upon the rear members of the harrow-supporting frame extending under the rear ends 35 of the front members of said frame, adjusting means for the latter, sprocket - wheels upon one of the traction-wheels and upon the shaft carrying the rotary harrow element, and 40 a chain connecting said sprocket-wheels.

2. In an implement of the class described, the combination of a wheel-supported main frame, a pivotally - mounted frame having jointed side pieces, a rotary harrow element 45 at the rear ends of said side pieces, the latter being so jointed together as to be capable of flexing downwardly, but not in an upward direction, and means for transmitting motion to the rotary harrow element from one of the 50 traction-wheels of the main frame.

In testimony that I claim the foregoing as my own I have hereto affixed my signature in the presence of two witnesses.

JOHN HENRY DAVIS.
